Primary Examiner — Angela J Lee*(74) Attorney, Agent, or Firm* — NSIP Law(57) **CLAIM**

The ornamental design for a display screen or portion thereof with graphical user interface, as shown and described.

DESCRIPTION

The FIGURE is a front view of a display screen or portion thereof with graphical user interface showing my new design. The broken line drawing of the portion of the display screen and the text/words, symbols and images in broken lines shown in FIG. 1 are for illustrative purposes only and form no part of the claimed design.

1 Claim, 1 Drawing Sheet
